UNITED STATES PATENT OFFICE.

SAMUEL G. BARNARD, OF SEATTLE, WASHINGTON.

SELF-LUBRICATING BOLT.

1,145,288.

Specification of Letters Patent.

Patented July 6, 1915.

Application filed July 21, 1914. Serial No. 852,280.

To all whom it may concern:

Be it known that I, SAMUEL G. BARNARD, a citizen of the United States, residing at Seattle, in the county of King and State of Washington, have invented new and useful Improvements in Self-Lubricating Bolts, of which the following is a specification.

The invention has relation to bolts for connecting parts required to be lubricated such as vehicle springs, connecting rods and like moving parts.

The invention has for its object to provide a bolt which automatically supplies oil to the moving parts connected thereby, said bolt having a longitudinal bore, a lateral outlet leading from such bore, a cap for closing the open end of the bore and an absorbent connected with such cap and removable from the bore of the bolt to admit of supplying the same with lubricant by dipping into a cup or other receptacle containing a quantity of oil.

The invention also consists of the novel features, details of construction and combination of parts, which hereinafter will be more particularly set forth, illustrated and claimed.

In the accompanying drawing: Figure 1 is a central longitudinal section of a self lubricating bolt embodying the invention. Fig. 2 is a detail view of the cap and absorbent connected therewith disassociated from the bolt. Fig. 3 is a modified form of cap and absorbent.

Corresponding and like parts are referred to in the following description and indicated in all the views of the drawing, by the same reference characters.

The numeral 1 designates a bolt such as commonly provided for connecting the part to be secured. A longitudinal bore 2 is formed in the bolt 1 and terminates a short distance from one end of such bolt. One or more lateral outlets 3 communicate with the bore 2. A cap 4 closes the open end of the bore 2 and is preferably connected with the bolt by means of a screw thread. A stem 5 projects from the cap 4 and is adapted to receive an absorbent which practically fills the bore 2. The absorbent may consist of a plurality of washers 6 of felt or other material of a nature to absorb a comparatively large quantity of oil. In the modification

shown in Fig. 3 the absorbent 7 consists of a single piece and may be connected to the cap 4 in any manner.

In the practical operation of the invention the cap 4 and oil distributer consisting of the absorbent connected with such cap are removed from the bolt and the absorbent part constituting the oil distributer is dipped into a quantity of oil contained in a cup or other receptacle until such absorbent is thoroughly saturated. The cap and absorbent are replaced and the oil taken up by the absorbent is gradually discharged and passes through the outlet 3 and lubricates the parts connected by means of the bolt. It will be understood that the absorbent may be quickly charged in a few moments by simply dipping in the manner stated. The excessive amount of oil taken up by the distributer is naturally discharged and passing from the bore 2 of the bolt through the outlet 3 lubricates the rubbing surfaces and thereby minimizes the wear thereon.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention what is claimed as new, is:—

1. A self lubricating bolt having a longitudinal bore and a lateral outlet, a cap fitted to one end of the bolt and closing the open end of the longitudinal bore, a stem projecting from the cap and adapted to enter the bore of the bolt, and a plurality of annular washers of absorbent material slipped upon the said stem and adapted to contain a quantity of oil for distribution.

2. A self lubricating bolt having a longitudinal bore and a lateral outlet, a cap fitted to one end of the bolt and closing the open end of the longitudinal bore, a stem project-

ing from the cap and adapted to enter the bore of the bolt, a plurality of annular washers of absorbent material slipped upon the said stem and adapted to contain a quantity of oil for distribution, and a nut threaded on the free end of said stem whereby said washers are held against movement.

In testimony whereof I affix my signature in presence of two witnesses.

SAMUEL G. BARNARD.

Witnesses:

HENRY S. FELTON,
J. ZINA COLTON.
